[54] ROOM THERMOSTAT OR SIMILAR ARTICLE

D. 249,652 9/1978 McElroy D10/51
3,999,158 12/1976 Rae 337/392

[75] Inventor: Norbert T. Wolfe, Minnetonka, Minn.

Primary Examiner—Nelson C. Holtje
Attorney, Agent, or Firm—Clyde C. Blinn

[73] Assignee: Honeywell Inc., Minneapolis, Minn.

[57] CLAIM

[**] Term: 14 Years

The ornamental design for a room thermostat or similar article, substantially as shown and described.

[21] Appl. No.: 845,175

DESCRIPTION

[22] Filed: Oct. 25, 1977

[51] Int. Cl. ..... D10—04
[52] U.S. Cl. D10/51; D10/50
[58] Field of Search D10/50, 51, 53, 60;
337/392, 380, 301, 84; 236/46 R; 200/139, 333

FIG. 1 is a front, top and right side perspective view of a room thermostat or a similar article showing my new design.

FIG. 2 is a left side elevational view of the room thermostat of FIG. 1, the right side being a mirror image thereof, and

FIG. 3 is a front elevational view of the room thermostat of FIG. 1.

The rear and bottom, not shown are conventional plain and unornamented.
